UNITED STATES PATENT OFFICE.

EDWARD W. CLARKE, OF KINGSTON-UPON-HULL, ENGLAND.

SUPPORT FOR BOILER-FLUES.

1,388,025.

Specification of Letters Patent. Patented Aug. 16, 1921.

Application filed November 9, 1920. Serial No. 422,972.

To all whom it may concern:

Be it known that I, EDWARD WILLIAM CLARKE, a subject of the King of Great Britain, residing at Kingston-upon-Hull, in the county of York, England, have invented certain new and useful Improvements in Supports for Boiler-Flues, for which I filed an application in England, August 25, 1919, and of which the following is a specification.

10 This invention has reference to means for temporarily jacking-up or supporting weak portions of the furnace flues or steam generators to prevent the same from extending or developing, until such time as the defect 15 can be repaired, and my said invention has for its object an improved simple and inexpensive device for the purpose mentioned which can be readily inserted in a flue and expanded to fit the flue at the point where 20 the weakness is present and be readily withdrawn after use, the device when in position forming an extremely strong support for the weak portion of the flue.

My invention resides in the employment 25 of a pair of strong metal members each in the form of a segment of a circle or ring, the said members being pivoted or hinged together at the top and being each provided at the bottom with a loosely mounted nut, and 30 of a right and left hand threaded spindle one end of which is screwed into the nut carried by the bottom end of one pivoted curved member and the other end of which is screwed into the nut carried by the bottom 35 end of the other pivoted curved member, the two pivoted members when their bottom ends are drawn toward one another by the threaded spindle, being reduced in size to enable the device to be inserted in the furnace 40 flue to the point where the weak portion of the flue is situated, and on being moved apart when in the required position, by such spindle, conform to and press against the inside of the flue and form a 45 strong metal arch which supports the weak part of the flue. Means are preferably provided for passing water through the device for preventing burning of the same.

Two or more of the devices may be connected together to form a double or multiple device, if desired.

In order that my invention may be readily understood and carried into effect, I have appended hereunto two sheets of explanatory drawings of which Figure 1 represents a transverse section of a furnace flue of a

steam generator showing one of my improved supporting devices inserted therein before being opened out to support the weak place in the flue, the fire-bars being shown 60 removed to allow of the insertion of the device; Fig. 2 is a similar view to Fig. 1 but shows the device opened out to fit the flue to support the weak part thereof, the fire-bars being shown reinstated; Fig. 3 represents a 65 longitudinal section on the line 3—3 of Fig. 2 but with the right and left handed threaded spindle of the device omitted; Fig. 4 is a plan view of a portion of the device showing the joint; Fig. 5 is a plan view of the 70 bottom part of one of the two hinged members of the device and of a portion of the right and left handed threaded spindle, and Fig. 6 represents a small portion of a plain flue and a portion of one of the pivoted 75 members having a plain outer face to suit the plain surface of the flue.

In constructing a jacking-up or supporting device for the purpose mentioned, in accordance with my invention, I employ two 80 strong metal members A and A¹ each of the shape of a segment of a circle or ring, each of which members is provided at the bottom with an inwardly projecting portion a. The said two members A and A¹ have their 85 top meeting edges pivoted together as at B, and between them normally form an arch which conforms to the cross section of the top and sides of the furnace flue when the device is in its opened out position in the 90 flue.

The inner ends of the inturned bottoms a of the members A, A¹ are provided with lugs to form a bifurcation in which are pivoted nuts C, C¹, and a right and left handed 95 threaded spindle D has one of its ends screwed into the nut C mounted in the bifurcated bottom end of one member and its other end screwed into the nut C¹ in the bifurcated bottom end of the other member, 100 the said spindle being provided with a nut-like enlargement d or with flats at the center of its length to take a spanner for use in rotating such spindle.

The segmental members A and A¹ are 105 preferably of semi-circular shape in cross section, the rounded face being outside when the device is for use in corrugated flues, (see Fig. 3 of the drawings) and inside when it is for use in plain flues, (see Fig. 6 of the 110 drawings).

For the purpose of preventing the burn-

ing of the device, I preferably provide the members A and A¹ with a bore or passage a¹ to allow of sea or other water being passed therethrough. One and a convenient arrangement for causing water to pass through the device consists of connecting a pipe E by a suitable coupling to the bottom of the passage through one pivoted member, and a second pipe E¹ by a similar coupling to the bottom of the passage through the other member, the said two pieces E and E¹ being carried out through the front of the flue and one of them carried down into the sea and the other connected to any approved form of pump, such as a bilge pump, the suction of the bilge pump causing sea water to be drawn through the device.

Any suitable number of the devices may be used in a flue, depending upon the weakness in the flue.

If desired, the devices may be duplicated, such a double device being shown in dotted lines in Fig. 3 of the drawings.

In constructing a double device, I employ two pairs of the metal members of the kind described, the two members forming a pair having their top meeting ends pivoted together as before described, the nuts in this arrangement being common to both pairs of pivoted members and being in the form of rods or shafts, one of which rods or shafts C' connects the two inturned bottom ends of two adjoining pivoted members, the other of which rods or shafts (not seen) connects the inturned bottom ends of the other two adjoining pivoted members, the said rods or shafts being loosely mounted in the inturned ends of the pivoted members which they connect, and being each provided with a lateral internally threaded hole about midway of their length.

One end of the right and left handed threaded spindle is turned into the threaded hole through one rod or shaft and the other end of such spindle is turned into the threaded hole through the other rod or shaft, the two pairs of pivoted members being simultaneously opened out or drawn together by rotating the threaded spindle in the required direction.

The sea or other water supply pipe is connected to the bore or passage through one member of one pair of members and the pipe connected with the bilge pump is connected to the bore or passage through the adjoining member of the other pair of pivoted members, the bores or passages through the other adjoining two pivoted members being connected by means of a pipe F, the water from the sea or other source of supply passing first through pivoted member to which the sea water or like supply pipe is connected,

through the other member of that particular pair of pivoted members, through the pipe F and thence through the adjoining member of the other pair of pivoted members, through the member pivoted thereto and to the bilge pump.

To insert the device in the flue, the fire-bars are first withdrawn, the spindle having a right and a left handed thread is rotated in the direction to draw the bottom ends of the two pivoted members, or of each pair of pivoted members, together, which reduces the size of the device and so enables it to be inserted in the flue to the point where the weak portion of the flue which requires supporting is situated. When the device is at the required point in the flue, the threaded spindle is rotated in the necessary direction to expand the pivoted members until they conform to and press against the inside of the flue, when they form a strong arch which braces or supports the weak part of the flue; the fire-bars being then replaced, and if the pivoted members are formed hollow, the sea water pipe and the pipe connected with the bilge pump are connected to the respective pivoted members when the device is a single one, or to two of the pivoted members and the connecting pipe to the other two pivoted members, if the device is a double one, the opening out of the pivoted members to their fullest extent bringing their top ends so tightly together as to connect the bore or passage through one member with that through the other member pivoted thereto whereby a continuous bore or passage is formed, the joint so formed being so tight as to prevent the escape of water at the junction of the two members.

I claim:—

The combination, with the horizontal fire flue of a boiler, of a support for the flue comprising two curved bars pivoted together at one end and adapted to fit in the flue with their free end portions extending downwardly below the axis of the said flue, said bars having longitudinal passages for cooling water formed in them and the pivoted end portions of the said bars being adapted to be placed in contact when the bars are expanded, so as to operatively connect the said passages, pipe connections for supplying cooling water to the said passages, and means for expanding the said bars arranged between their lower end portions.

In testimony whereof I affix my signature in the presence of two witnesses.

EDWARD W. CLARKE.
